UNITED STATES PATENT OFFICE.

WILLIAM J. MURPHY, OF ST. PAUL, MINNESOTA.

SANITARY REFRIGERATOR SUPPORT.

Application filed March 21, 1924. Serial No. 700,942.

To all whom it may concern:

Be it known that I, WILLIAM J. MURPHY, a citizen of the United States, residing at St. Paul, in the county of Ramsey and State 5 of Minnesota, have invented certain new and useful Improvements in Sanitary Refrigerator Supports, of which the following is a specification.

The present invention relates to a sanitary support for refrigerators.

When a refrigerator is placed directly upon the floor, the sides thereof, which usually come almost flush with the floor, afford an immediate inaccessible housing for dirt, 15 moisture, and vermin which make for unsanitary conditions.

An object of the present invention is to elevate a refrigerator to facilitate cleaning in the vicinity thereof.

Another object is to movably support a refrigerator to improve the sanitary surrounding conditions thereof.

In order to attain these objects there is provided in accordance with one feature of 25 the invention, an adjustable frame of metal tubing supported on pivoted rollers having pins integral with movable sleeves connected to the tubing thereof, which pins may be inserted in the caster holes of a refrigerator to support it and prevent relative movement 30 between the supporting frame and the refrigerator.

These and other features of the invention will be more specifically designated in the 35 following description and the accompanying drawing, wherein:

Figure 1, is a view in isometric projection of a supporting frame made in accordance with the present invention, showing a portion 40 of a refrigerator supported thereon.

Figure 2, is a view in longitudinal section of the adjustable portion of a tubular side frame member.

Figure 3, is a view in side elevation of a 45 refrigerator positioning pin as carried by a slideable sleeve which is mounted on a side member of the supporting frame; and

Figure 4, is a view of a supporting roller which may be used with the supporting 50 frame, a portion thereof being broken away to show rollers which facilitate pivoting movement thereof.

Referring to the drawings in detail, a 55 frame A is composed of metal tubing where- in four corner members 1, which may be

three-way ninety-degree pipe fittings, each of which has screwed in a lower outlet 2 thereof, a vertical supporting leg 3. Each pipe fitting or corner member is provided with an opening 4 sufficiently larger than 60 the third opening 5 of each corner fitting 1 to receive a pipe 6 which will be large enough to telescopically contain a pipe 7 to be inserted in the small opening 5. A sleeve 8 has integral therewith a pin 9 of a size to 65 conveniently fit within a caster opening of a standard size. Thumb screws 10 may be placed on the opposite side from pin 9 to secure sleeves 8 at desired positions on the tubular frame members. Four of these 70 sleeves and pin supports are illustrated, one on each corner of the frame. Diagonal supports 11 may be welded across the corners, as shown, to additionally brace and strengthen the frame. A thumb screw 12 is 75 provided on each of the larger tubular frame members 6 of each corner unit, and are placed adjacent the open end of each frame member 6 to which they are fitted to grip the smaller pipe 7 telescopically inserted therein. Casters 13 are provided on the lower extremity of each corner upright to provide a rolling support for the frame. Any sturdy caster, capable of maintaining a pivoted rolling support under considerable 80 weight, is applicable to this use, the one illustrated in Figure 4 being a desirable type.

The wheels 14 thereof and rolling supports 85 15 form the pivoting means thereof, insuring ready movability of the refrigerator supported thereby at all times. The casters may be affixed to the legs 3 by inserting wooden 90 plugs 16 in the ends of the legs and drilling a central hole in each plug to receive a pin 17 of the caster, a disc washer 18 being 95 inserted as shown to provide a track for the rolling supports 15. Of four corner units required to make a frame A, as shown in Figure 1, two kinds of corner units are 100 required, namely, the kind shown at B which has a small diameter long pipe, and a large diameter short pipe; and the kind shown at C which is provided with a small diameter short pipe, and a large diameter long pipe. Adjacent corner pieces are dissimilar, and diagonally opposite ones are similar. 105 From this it may be seen that but two or three sizes of frame corner units are required to handle all types of refrigerators, from the smallest to the largest, inasmuch 110

as each frame is capable of adjustment over a distance varying from eight to eighteen inches.

A rack E for supporting a drip pan F may be composed of strong wire, welded together and supported by loops 20 encircling the telescoping frame members of the support A. This leaves the entire floor beneath a refrigerator accessible for cleaning and open 10 to light and air, thereby promoting sanitation.

In using the support, the sleeves 8 are placed a sufficient distance from the corner fittings 1 to bring each outside corner of a 15 refrigerator D in line with a leg 3. The frame thumb screws 12 are then loosened and the frame adjusted to the approximate size of the refrigerator. The refrigerator is then lifted onto the frame A which is readily ad- 20 justed by telescopically moving the corner members thereof to permit the pins 9 to be inserted into the caster holes in the refrigerator, which is then lowered into position on the frame A. Thumb screws 12 are then 25 screwed in to secure the telescoping members in position. The refrigerator when thus supported in a raised position is more easily accessible, especially the bottom shelves

thereof, access to which in its normal low position is exceedingly difficult and sometimes compels a housewife to get down on one knee to remove an article therefrom. Furthermore, it is a simple matter to sweep or mop under a refrigerator when it is in a raised position, and, light and air having ready access to the floor under the refrigerator, prevents the existence of a damp condition there which is sometimes sufficient to taint food such as butter, cream, and the like, and to rot the floor beneath a refrigerator resting directly on the floor. When it is desired to clean down the walls surrounding a refrigerator, the refrigerator may be readily moved out by grasping a side frame member and pulling it out on the casters 3. 40 45

What I claim is:

A refrigerator support comprising upright corner posts, telescopically adjustable frame members connecting the corner posts, and sleeve means slidable on the adjustable members each of said means having a pin integral therewith to penetrate a caster opening in a refrigerator.

In testimony whereof I affix my signature.

WILLIAM J. MURPHY.
